JOINTED FIGURE TOY

George H. Seligson, New York, N. Y.

Application February 10, 1948, Serial No. 7,417

11 Claims. (Cl. 46—161)

1

My invention relates to a figure such as a doll, mannikin, or the like, provided with movable appendages, and more particularly to a toy figure with easily assembled arms and legs.

The primary object of my invention is to provide a figure with seamless sockets to permit the appendages or limbs to be freely rotatable therein.

Other objects are to provide a novel method of assembling the limbs to a doll that will reduce manufacturing costs such as the number of imperfect assemblies; to provide an assembly wherein the movement of one limb will cause one or more of the remaining limbs to move; to provide a central post within the doll for holding the limbs in position in their sockets as well as to provide means for rotating the limbs; to provide such a post terminating externally in a head section; to provide a body section for the doll divided into transverse or longitudinal portions without causing a seam in the limb sockets; to provide means for securing the transversely sectional doll portions, while allowing the two portions to rotate one with respect to the other; to provide a doll wherein the limbs may be inserted into their sockets from the inside; to provide limbs with enlarged end sections retaining the limbs in their sockets when inserted from the inside; to provide a doll body having socket apertures, and other openings through which the entire limbs are inserted to be positioned into their respective sockets; to provide limbs having internal engaging surfaces for causing the limbs to be moved thereby; to provide a doll with an inside post provided with a spring wound mechanism for causing the limbs to be rotated thereby; to provide a doll with a hollow central post; and to provide a figure having the foregoing characteristics which can be made of moulded parts at lower cost than previous types of so called animated toy figures.

I accomplish these and other objects and obtain my new results as will be apparent from the device described in the following specification, particularly pointed out in the claim, and illustrated in the accompanying drawing, in which:

Fig. 1 is a front elevation of one form of my invention, in the form of a doll partially in section.

Fig. 2 is a top-transverse sectional view taken in the plane 2—2 of Fig. 1.

Fig. 3 is a similar view taken in the plane 3—3 of Fig. 1.

Fig. 4 is a perspective view of the upper portion of the doll body illustrating the method of assembling one of the arms through the transverse body opening into the arm socket.

2

Fig. 5 is a similar view illustrating the method of inserting the arm through the head opening of the body section.

Fig. 6 is a perspective view of the method of inserting the doll's leg into its socket.

Fig. 7 is a front sectional view illustrating a modified form of enlarged ends of arms in contact with each other.

Fig. 8 is a similar view illustration, of a further modification.

Fig. 9 is a diagrammatic view of a spring wound mechanism for causing movement in the doll parts.

Fig. 10 is a front sectional view of a modified form of central post and limb engaging means.

Fig. 11 is a top plan view of an animal figure, illustrating a longitudinally sectional body section.

As shown in Fig. 1 of the drawing, a preferred embodiment of my invention comprises the upper hollow body section 10, lower hollow body section 11, arms 12 and 13, legs 14 and 15 and head section 16.

The upper body section contains a head aperture 17, and a transverse body opening 18 through which opening and aperture the longitudinally positioned central post 19 extends, terminating in the head section 16. The opening 18 is shaped to form a peripheral seat 20 for positioning the edge 20a of the lower body section which forms the transverse opening 21. At the bottom of the lower body section, an aperture 22 is located through which the end portion of post 19 protrudes, where it is flattened, as at 23 to form a rivet-like fastening means for holding all the parts together.

The longitudinally extending post may be made hollow as at 24, connecting with the mouth 25 of the head, to create a liquid passageway to opening 26.

Arms 12 and 13 are positioned in openings 27 and 28 respectively, the enlarged circumferential flanges or shoulder portions 29 and 30 maintaining the arms in movable position in the openings.

Projecting from the flanges 29 and 30 are collars 31 and 32 respectively, for a purpose hereinafter described.

In the lower body section 11, the leg openings 33 and 34 are located, into which openings the legs 14 and 15 are inserted. The legs terminate in peripheral flanges 35 and 36 for movably retaining the legs in position.

The longitudinally extending post is provided with a circular shoulder section 37, adjacent and

engaging the circular collars 31 and 32, and a circular shoulder section 38 engaging the contacting surfaces of peripheral flanges 35 and 36. Resilient washers 39 and 40 may be interposed between shoulder 37 and its engaging collars, and between shoulder 38 and its engaging flanges respectively. The washers are suitably secured to the circular shoulders, as by gluing, to prevent separation, and they provide a resilient engaging surface which maintains contact between shoulders and collars or flanges, as the case may be, to take up any wear that may occur.

It will thus be seen that rotating the head will cause the collars and flanges of the arms and legs respectively to rotate causing movement in the appendages.

The method of assembling the arms and legs to the body sections is shown in Figs. 4, 5, and 6.

In Fig. 4, the arm 13 is shown in the stage of being inserted through opening 18 of body section 10, into arm opening 28. The final position is shown in Fig. 1. Should the upper portion of the body section be made integral with the lower portion, as shown in Fig. 5, the arm 13a may be inserted through the head opening 17a into arm opening 28a, to enable the arms to be properly positioned in their openings.

The legs are similarly inserted, either through opening 21 in the lower body section 11, into the respective leg openings, as shown in Fig. 1, or through the head opening, as described above, and as shown in the fragmentary view of Fig. 6 where the leg 14a is shown partially projecting through leg opening 33a, in the lower portion of the body section 10a.

In all versions the arms and legs are first inserted fingers and toes projecting forward into the hollow body, and then through the hollow body into their respective appendage openings until the flanges position themselves against the inner wall about the openings.

The contacting surfaces of collars 31 and 32, flanges 35 and 36, and shoulders 37 and 38 may be roughened to insure frictional engagement with each other. Instead of relying on friction, they may be toothed for interlocking the contacting surfaces to insure movement despite any wear, thus eliminating the need for resilient washers. By reducing the diameter of the collars and lower flanges, movement of the central longitudinal post will cause a greater movement in the appendages. Any shape or type of contacting surfaces may be employed which will transmit the movement of one part to the other. Moreover a movement of one arm or leg will cause a movement of all remaining appendages including the head. Rotating the body portions with respect to one another or with respect to the head will also cause the appendages to move in their openings.

In Fig. 7, is shown a modification, wherein the arms 12b and 13b are inserted into openings 27b and 28b, of the body portion 10b, the enlarged portion of the arms, 29b and 30b, constituting a ball and socket arrangement respectively, the socket 32b receiving the ball 29b. One of the arms may thus be rotated, causing the other to move similarly.

In Fig. 8, the arms 12c and 13c are provided with contacting ball shaped ends 29c and 30c, the openings 27c and 28c being socket shaped, as at 27d and 28d respectively. In contrast with arms 12b and 13b of Fig. 7 which may only be rotated, arms 12c and 13c may be moved in any direction, the friction between the balls causing

one to move the other, the balls being kept in position in their sockets.

In both Fig. 7 and Fig. 8 modifications, the parts are slightly sprung when inserted, causing them to snap into proper position under a retaining pressure. The walls of the body portion may also be slightly flexed in such assembly to assist in the positioning of the parts.

In Fig. 9, a spring wound movement 40 is illustrated diagrammatically positioned about the post 19a, with one end 41 corresponding to the key winding of the movement being secured to the post and the other fixed end 42 of the movement being secured to the body portion 10e. The movement is wound by rotating the post while holding the body portion 10e. When the winding pressure is released the post will rotate, causing the engaging arms and legs, and the head, not shown, to move likewise. The spring wound mechanism is not shown in detail, its design being well known, and shown in prior art patents.

In Fig. 10, a modified form of my device is shown characterized by the two body portions 10c and 11c with associated appendages being secured together with the contacting shoulder parts in between. Thus the shoulders 37c and 38c are joined on the post 19c and the upper and lower body portions are assembled thereabout. The head in this form may be secured to the post as by threading, thus serving to hold the body portions together with the lower end of the post flattened, as previously shown in Fig. 1.

In Fig. 11, I have illustrated an animal figure indicating how the body section may be longitudinally divided into two portions 10d and 11d, held together by a transverse post or pin 19d, the ends 23d of which are flattened to secure the two body sections together. The front appendages 12d and 13d and rear appendages 14d and 15d, terminate in enlarged ball shaped ends, such as 29d and 30d, 35d and 36d respectively, each pair of which may contact each other in a manner similar to that shown in Fig. 8. The head section 16d, and a tail 50 are positioned in apertures 17d and 50d respectively, formed at the junction of the two body portions, and terminate in enlarged ball shaped ends 16e and 50e, each engaging one of the aforementioned enlarged ball shaped appendages, such as 29d, and 35d, as illustrated. Thus movement of either the tail or either rear leg will cause the remaining two rear appendages to move. Similarly, movement of either the head or either of the front legs will cause the remaining two front appendages to move. As has been explained the contacting surfaces should be roughened or suitably provided with surfaces that will not cause slippage of the contacting parts unless such slippage is intended to avoid breaking of the parts under excess stresses.

The various parts may be made of any suitable material, such as the thermoplastics, which are rigid at room temperatures, and can be moulded or otherwise shaped. The parts are preferably made so that the openings containing rotating or movable parts are free of seams or mould marks which would interfere with the free movement of the parts. Glue or other adhesives which are required in many doll assemblies, where the parts are permanently placed in position are not required here, with the result that the seepage of adhesives on rotating surfaces causing a permanent lock, is avoided.

The uniqueness of the assembly permits a substantially retaining element of each appendage

to be freely positioned inside the body of the doll or figure. The figures may be sectioned longitudinally or transversely, the latter possessing the advantage of enabling the upper and lower portions of the body to rotate with respect to each other simulating a body posture partially obtainable in life.

The invention may be incorporated advantageously in all types of figures, human or animal.

I have thus described my invention, but I desire it understood that it is not confined to the particular forms or uses shown and described, the same being merely illustrative, and that the invention may be carried out in other ways without departing from the spirit of my invention, and, therefore, I claim broadly the right to employ all equivalent instrumentalities coming within the scope of the appended claims, and by means of which, objects of my invention are attained, and new results accomplished, as it is obvious that the particular embodiments here shown and described are only some of the many that can be employed to attain these objects and accomplish these results.

What I claim and desire to secure by Letters Patent, is as follows:

1. A doll-like figure having a body section and appendages, said body section and appendages having a shape representing a life-like figure, one of said appendages having an enlarged end portion, said body section having a hollowed portion provided with a plurality of openings, one of said openings being larger than the enlarged end portion of the appendage to permit it to be entirely inserted inside the body section, another of said openings being smaller than the said enlarged end portion to prevent it from passing therethrough, said appendage extending through the smaller opening with the enlarged end portion inside the body, retaining the appendage in position, said appendage being movable with respect to the body section and provided with means positioned inside the body preventing inner movement of the appendage in the axis of the smaller opening, said body section being provided with a surface portion conforming to the configuration of the doll-like figure, covering the larger opening.

2. The figure of claim 1, wherein the appendage is made of rigid material and the enlarged end portion of the appendage is made integral with the appendage, requiring the appendage itself to be inserted through both of said openings.

3. The figure of claim 1, wherein the body section comprises two hollow portions, each having a plurality of openings one of said openings corresponding to the larger opening, and another of said openings corresponding to the smaller opening, and means rotatably securing the two hollow portions to each other with the larger openings abutting each other.

4. The figure of claim 3, one of said hollow portions being rotatably mounted on a seat provided in the other hollow portion.

5. The figure of claim 1 wherein the opening for the appendage is provided with a seat accessible to the inside of the body portion into which the enlarged end of the appendage is located.

6. The figure of claim 1, wherein the enlarged end of the appendage is substantially ball shaped, and the appendage opening is provided in the

hollow side thereof with a ball shaped seat to give the appendage a substantially universal movement in the seat.

7. The figure of claim 1, wherein a head section is positioned in the largest opening.

8. The method of assembling a doll-like figure having a hollow body section containing a plurality of openings, one being larger than the other, and an appendage having an enlarged end portion said body section and appendage having a shape representing a life-like figure, which comprises the step of inserting the enlarged end portion entirely through the larger opening, and supporting the appendage in the smaller opening with the enlarged end portion of the appendage inside the body section with the remainder of the appendage extending through the smaller opening and rotatably supported in position therein, then inserting a positioning means inside the body section preventing inner movement of the appendage in the axis of the smaller opening, and finally closing the larger of the openings with a surface portion conforming to the configuration of the doll-like figure.

9. The figure of claim 1, wherein the body section comprises two hollow portions secured together by a hollow member extending through the body section, each hollow portion having a plurality of openings supporting appendages therein.

10. The figure of claim 1, wherein the enlarged end portion is made integral with the appendage requiring the appendage itself to be inserted through both of said openings, and the body section is provided with opposed openings, appendages like said one appendage positioned therein, and an extending member positioned between the enlarged ends of the opposed appendages, said extending member terminating in an externally positioned head portion for the figure.

11. The figure of claim 1, wherein the enlarged end portion of the said one appendage is made integral with the appendage requiring the appendage itself to be inserted through both of said openings, and the body section is provided with an extending member positioned between the inner ends of two of the said one appendages, and a resilient member positioned between the appendages and the extending member to establish resilient contact between the two for mutual movement therebetween.
